UNITED STATES PATENT OFFICE

128,476

DESIGN FOR A SLIDE WHISTLE

Maurice H. Berlin, Chicago, Ill., assignor to Chicago Musical Instrument Co., Chicago, Ill., a corporation of Illinois

Application May 19, 1941, Serial No. 101,006

Term of patent 14 years

To all whom it may concern:

Be it known that I, Maurice H. Berlin, a citizen of the United States, residing at Chicago, in the county of Cook and State of Illinois, have invented a new, original, and ornamental Design for a Slide Whistle, of which the following is a specification, reference being had to the accompanying drawing forming part thereof.

In the drawing:

Fig. 1 is a top plan view of a slide whistle, showing my new design.

Fig. 2 is a side elevational view of the same.

Figs. 3 and 4 are opposite end elevational views thereof.

I claim:

The ornamental design for a slide whistle, as shown.

MAURICE H. BERLIN.
